UNITED STATES PATENT OFFICE.

MAMIE P. WHIDDEN, OF FORT MYERS, FLORIDA.

LIFE-PRESERVING GARMENT.

1,129,932.

Specification of Letters Patent.

Patented Mar. 2, 1915.

Application filed October 28, 1914. Serial No. 869,022.

To all whom it may concern:

Be it known that I, MAMIE P. WHIDDEN, a citizen of the United States, residing at Fort Myers, in the county of Lee and State 5 of Florida, have invented certain new and useful Improvements in Life-Preserving Garments, of which the following is a specification.

My invention relates to improvements in 10 life saving apparatus, and has particular reference to apparel to cover the body or head or both, for excluding the water therefrom, preventing undue reduction in the temperature or freezing of the body, or 15 parts thereof, which frequently causes illness or death.

An important object of the invention is 20 to provide a life saving garment of the above mentioned character adapted to fit over the clothes of the wearer, and which may be put on in a convenient and expeditious manner.

A further object of the invention is to provide means to protect the head of the wearer 25 from the sun, the same also serving to suspend the head, when the wearer is floating upon the back.

A further object of the invention is to provide simple and strong means to detachably 30 connect the hood or head-receiving portion of the apparel with the body portion thereof.

Other objects and advantages of the invention will be apparent during the course 35 of the following description.

In the accompanying drawings forming a part of this specification and in which like numerals are employed to designate like parts throughout the same, Figure 1 is a 40 front elevation of apparatus embodying my invention, showing the same in use, Fig. 2 is a front elevation of the hood or head covering member removed, Fig. 3 is a side elevation of the same, Fig. 4 is a side elevation 45 of the apparatus in use, with the hood or head covering member removed, Fig. 5 is a front elevation of the apparatus, showing the neck-band distended, Fig. 6 is a front elevation of the same, showing the neck-band contracted, Fig. 7 is a plan view of the

neck-band contracted, and, Fig. 8 is a similar view of the neck-band distended.

In the drawings, wherein for the purpose of illustration is shown a preferred embodiment of my invention, the numeral 10 designates the body-receiving portion of the apparatus or garment, which is formed of impermeable or substantially impermeable flexible material, such as rubberized silk, although any other suitable material may be employed. This body-receiving portion carries depending leg-receiving portions 11, preferably slightly split at their lower ends, as shown at 12. Attached to the lower ends of these leg-receiving portions are feet-receiving portions 13. Attached to the upper end of the body-receiving portion 10 are arm-receiving portions 14. The arm-receiving portions and the feet-receiving portions are of course closed at their ends. It is thus seen that I provide an impermeable one-piece garment, whereby the water is effectually excluded from the person of the wearer. The body-receiving portion 10 is opened at the top, such opening being 75 formed by an expandable and contractible neck-band 15, shown more clearly in Figs. 5 to 8 inclusive. This neck-band 15 is suitably large when expanded, being larger than the waist of the wearer, enabling the wearer to 80 enter the garment solely through this opening. This garment is made amply full whereby the wearer may thoroughly protect himself against cold, by wearing an overcoat and other apparel.

Means are provided to contract the neck-band whereby the same will fit around the neck or upon the shoulders of the wearer, preventing the body-receiving portion from sagging or dropping down from the shoulders. This is accomplished by folding the back and front of the body-receiving portion 90 10 along longitudinal lines 16 and 17. In Figs. 5 and 8, the neck-band 15 is shown as expanded, while in Figs. 6 and 7, the same is 95 shown contracted and held in this position by detachable ball and socket catches or clips 18, such as ordinarily used upon kid gloves, the ball and socket members being attached to suitable portions of the body- 100

receiving portion 10, as is obvious. While this is the preferred manner of retaining the neck-band contracted, it is obvious that other means may be employed.

5 The numeral 19 (see more particularly Figs. 1 to 3 inclusive), designates a hood or head-receiving member, which is preferably approximately conical and decreases in diameter upwardly, as shown. This hood 10 is also formed of impermeable material, such as rubberized silk or the like. In order that this hood may be readily and securely detachably connected with the body-receiving portion 10, the hood is provided at its 15 lower end and at diametrically opposite points with arm-receiving portions 20, through which the arm-receiving portions 14 are passed. This hood is preferably further detachably connected with the body receiving portion 10 by detachable ball and 20 socket catches, the ball elements 22 thereof being preferably secured to the body-receiving portion 10, while the socket elements 23 are preferably attached to the inner surface of the hood 19, adjacent the lower end thereof. The hood 19 is provided in its 25 front or face with an opening 24, for the eyes and nose of the wearer, whereby suitable ventilation is provided. It is thus apparent that the lower portion of the hood 19 extends over the shoulders below the arm pits, thus thoroughly over-lapping the neck-band, to exclude the water at this point.

To protect the wearer from the heat of 35 the sun, I provide a head-shade or umbrella, in the form of a relatively flat approximately horizontal cylindrical bag or casing 25, formed of impermeable material, such as rubberized silk, the same being adapted 40 to be inflated with air, and having a valve 26 to allow of such inflating and to retain the air therein, as shown. The inflatable head-shade 25 is preferably secured directly upon the upper end of the hood, whereby 45 when the same is inflated it will be retained in the horizontal position. When the wearer is in the upright position in the water, this head-shade will protect the head from the rays of light from the sun, preventing sun strokes or the like. When the wearer is inclined or floating upon the back, it is obvious that this inflated head-shade will serve as means to suspend the head, thus preventing drowning.

50 In the use of the apparatus or garment, the wearer may have on such apparel as will be necessary to keep him suitably warm, such as an overcoat or the like. He enters the garment through the expanded neck-band 15, his arms and legs extending into the arm and leg-receiving portions of the 60 same. The neck-band is then contracted and secured in such position. The hood

19 is then placed over the head and the arm-receiving portions 14 pass through the openings 20, whereby the hood is securely fastened to the body-receiving portion 10. The hood is further connected with the body-receiving portion by the ball and socket catches. The head-shade 25 is now inflated, 70 thus providing effectual means for preventing the rays of light directly striking the head, the heat therefrom being absorbed by the air within this head-shade, and also to suspend the head if the wearer is floating 75 upon the back.

An ordinary life preserver 27 is placed around the waist of the wearer exteriorly of the body-receiving portion 10 of the garment, and serves to suspend him in the 80 water.

It is obvious that my garment may be used by men, women, or children, and may be made in various sizes. I do not wish to restrict myself to any particular manner of 85 cutting the portions of the one-piece garment, or securing or sewing the same together, as the same may be accomplished in different ways, so long as a garment is produced which possesses the advantages of my 90 construction.

It is to be understood that the form of my invention herewith shown and described is to be taken as a preferred example of the same, and that various changes in the shape, 95 size, and arrangement of parts may be resorted to without departing from the spirit of the invention or the scope of the subjoined claims.

Having thus described my invention, I 100 claim:-

1. A life saving garment, comprising a body receiving portion formed of substantially impermeable material and adapted to extend up to and about the neck of the 105 wearer and embodying arm and leg-receiving portions; in combination with a hood formed of substantially impermeable material and provided with a head receiving portion having a peep opening formed upon the forward side thereof, decreasing in diameter upwardly and increasing in diameter downwardly to provide a lower shoulder receiving portion adapted to overlap the body receiving portion and having arm-receiving 110 openings with their lower sides permanently closed; means detachably connecting the shoulder receiving portion and the body receiving portion between the arm-receiving openings; and an inflatable head shade attached to the upper reduced end of the hood and extending laterally therebeyond in spaced relation thereto for a substantial 115 distance.

2. In a life saving garment, a hood formed 125 of substantially impermeable material and

provided with a head receiving portion having a peep opening formed upon the forward side thereof, decreasing in diameter upwardly and increasing in diameter downwardly to provide a lower shoulder receiving portion having arm receiving openings with their lower sides permanently closed; and an inflatable head shade attached to the upper reduced end of the hood and extend-

ing laterally therebeyond in spaced relation to thereto for a substantial distance.

In testimony whereof I affix my signature in presence of two witnesses.

MAMIE P. WHIDDEN.
